UNITED STATES PATENT OFFICE.

GEORGE BROWNING, OF GRAND RAPIDS, MICHIGAN.

SAFETY-RAZOR.

1,368,693.

Specification of Letters Patent. Patented Feb. 15, 1921.

Application filed November 18, 1916. Serial No. 130,969.

To all whom it may concern:

Be it known that I, GEORGE BROWNING, a subject of the King of England, residing at Grand Rapids, in the county of Kent and State of Michigan, have invented certain new and useful Improvements in Safety-Razors, of which the following is a description.

My invention relates to that class of devices known as razors and especially to that class of razors wherein the cutting blade is positioned in a handle or holder provided with teeth or fingers arranged in suitable position in relation to the cutting edge of the blade to prevent the liability of cutting the flesh when the razor is in service.

The object of my invention is to provide a simple, convenient, efficient and altogether desirable device of the kind described wherein in among other advantages the cutting blade is moved longitudinally as well as laterally when in operation, thus greatly improving the operation of the device.

To this end my invention consists in the novel construction, arrangement and combination of parts herein shown and described, and more particularly pointed out in the claims.

In the accompanying drawings wherein like or similar reference characters indicate like or corresponding parts:

Figure 1 is an end elevation of my improved razor.

Fig. 2 is a similar view from the opposite side of the blade-holder and with the handle removed.

Fig. 3 is a section taken substantially on line 3—3 of Fig. 1.

Fig. 4 is a section taken substantially on line 4—4 of Fig. 3.

In the form shown my device comprises a handle 1 formed of any suitable material provided with a transverse head 2 at one end rigidly attached thereto and positioned at a suitable angle to the handle to provide for the proper application of the blade to the face. The head 2 is preferably of suitable length to provide a backing for the blade-holder mounted thereon and is also preferably provided with a guard for the cutting edge comprising a plurality of fingers 3 each preferably projecting into the cutting plane of the blade and extending laterally beyond the cutting edge 4 in position to prevent accidental injury from the edge of the

blade. Any convenient means may be provided for mounting the blade 4 in suitable position upon the head 2 and providing for longitudinally moving the same when my improved razor is in service. As shown a 60 blade-holder 5 is mounted upon the head 2 comprising a base 6 having a pair of laterally extending lugs or buttons 7 one at each end of the base each rigidly attached thereto and each extending through a slot 8 in 65 the head 2. The walls of the slots 8 are each substantially parallel to the margin of the head 2 and the buttons 7 are provided with suitably enlarged heads adapted to engage the underside of the head 2 to retain 70 the part 6 in position upon the head, yet permit of its free longitudinal movement thereon.

A pair of projecting pins or studs 9 are also provided upon the part 6 adapted to extend through suitable openings in the blade 4 and project at the outer face thereof to rigidly hold the blade in position when in service.

A cap 10 is pivotally attached to one end 80 of the part 6 as at 18 with suitable openings therein to receive the studs 9 and clamp the blade in position upon the part 6. Suitable means are also provided to lock the cap 10 to the part 6 at its free end. As shown a 85 resilient tongue or latch 11 is formed upon the cap at its free end adapted to engage the end of the part 6 and resiliently maintain the parts in position. Any convenient means may be provided for imparting a longitudinal reciprocating motion to the blade-holder 5. In the preferred construction an arm 12 is provided at each end of the head 2 projecting beyond the blade-holder 5 substantially in line with the handle 1 but 90 at the opposite side of the head and a roller 14 is rotatably mounted between the arms 12 and arranged to freely rotate on suitable bearings formed in said arms. A portion 15 at each end of the roller is formed to operate as a cam preferably having two projections substantially parallel with the axis of the roller at each end thereof so formed that arms 16—16 upon the rear of the part 6 will co-operate with the parts 15 at the opposite ends of the roller to move the blade-holder longitudinally when the roller is rotated and to accurately control the longitudinal position of the blade-holder upon the head 2.

The several parts are so formed that when the roller 14 is in contact with a surface the cutting edge of the blade 4 will be at the most advantageous angle to said surface for shaving the surface, thereby providing a guide for accurately controlling the angle at which the blade is presented to the surface to be operated upon. When in service the roller 14 contacts with the surface being operated on 10 thereby rotating the roller at each lateral movement of the blade in the shaving operation and the rotations of the roller, the surface of which is preferably fluted or roughened slightly to insure its proper engagement with the shaved surface, reciprocates the blade longitudinally thus securing the well known draw stroke in the cutting operation.

Having thus described my improvement it 20 is obvious that various immaterial modifications may be made in my device without departing from the spirit of my invention, hence I do not wish to be understood as limiting myself to the exact form or construction shown.

What I claim as new and desire to secure by Letters Patent is:

1. A safety razor of the class described comprising a guard plate having a handle 30 extending therefrom and provided with slots, a blade-holding unit slidably mounted

upon said plate, the blade-holding unit including a blade and a blade holder, said holder having guides engaging the lower surface of the plate, portions of said guides 35 extending through the slots in the plate, means on the holder engaging the blade to hold it in position, said holder having a clamping bar extending over and engaging the outer surface of the blade and portions 40 of the holder to clamp the blade securely with reference to the holder and means for reciprocating the blade-holding unit.

2. In a razor of the kind described and in combination, a flat head plate having a handle extending therefrom, a blade adapted to have reciprocatory sliding movement along the head plate, means detachably secured to the head plate for maintaining the blade upon the head plate while permitting the 50 same to reciprocate relatively to the head plate, a rotatable roller on the head plate located to one side thereof adjacent the rear edge of the blade, and a reciprocating drive connection for the blade with the roller.

In testimony whereof I have hereunto signed my name in the presence of two subscribing witnesses.

GEORGE BROWNING.
